J. T. ASHTON

SUPPORTING DEVICE

Filed July 3, 1924

Inventor
John T. Ashton

By *John R. Tomlin*
Attorney

UNITED STATES PATENT OFFICE.

JOHN T. ASHTON, OF ALEXANDRIA, VIRGINIA.

SUPPORTING DEVICE.

Application filed July 3, 1924. Serial No. 724,009.

To all whom it may concern:

Be it known that I, JOHN T. ASHTON, a citizen of the United States, residing at Alexandria, in the county of Alexandria and 5 State of Virginia, have invented certain new and useful Improvements in Supporting Devices, of which the following is a specification.

This invention relates to means for supporting absorbent or other suitable material upon a finger of a person.

An object of this invention is to provide a device for holding gauze, absorbent cotton or other suitable material upon the finger 15 of the user in convenient position for wiping, sterilizing, cleaning or polishing an instrument or tool.

Another object of this invention is to provide a device for supporting desired material upon the finger of the user, and constructed so that the material itself cooperates with the components of the device for securely gripping the finger of the user.

A further object of this invention is to provide a device for holding desired material upon the finger of the user and arranged to release the finger when the material has been removed from the holding device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

The invention has been illustrated in its preferred embodiments in the accompanying drawings, wherein:

Figure 1 is a perspective view depicting the invention in use;

Figure 2 is a side elevation of the device in its normal gripping position, the user's finger and absorbent material being indicated by dotted lines;

Figure 3 is a similar view, but showing the device in its released position;

Figure 4 is a top plan of the device per se; and

Figure 5 is a fragmental perspective view of one component of the device.

The device constituting this invention in-

cludes opposed members or levers 10, which are preferably formed of sheet metal, although it is to be understood that any suitable material may be employed as manufacturing conditions may require. Each member 10 comprises a resilient curvilinear finger-engaging member 11 and an angularly disposed gripper member 12, each gripper member 12 having a gripping flange 13 extending inwardly therefrom, and the inner or adjacent edges 14 of the flanges 13 are preferably straight, as shown.

Opposed pivot ears 15 extend perpendicularly from the intermediate portions of the members 10 and these ears are provided with apertures 16 for the reception of a pivot pin 70 or member 17, thereby pivotally uniting the members 10.

In use the cotton, gauze or other suitable material C is inserted between the flanges 13 of the gripper members 12 while the gripper members are in their extreme open position. Now the gripper members are partially closed and the finger-engaging portions placed over the thumb of the left hand of the user. While the thumb is being inserted between the finger-engaging members 11, the absorbent material C yields to permit the finger-engaging members to slip over the thumb or finger and this is also aided by the resiliency of the finger-engaging members. If an oversized portion of material is placed between the gripper member 12 the resilient finger-engaging members 11 will yield sufficiently to accommodate the thumb or finger of the user.

It will be manifest from this disclosure that the device will be especially useful and advantageous to dentists, doctors, and other professional practitioners, as well as mechanics and other workers in the many arts which employ instruments that require frequent cleaning, sterilizing, polishing or temporary replenishment. When employed as a depository or cleaner, a quantity of gauze, cotton, or the like is conveniently inserted in the device and, if desired, this material may be saturated or coated with some approved sterilizing material and employed either as a cleaner or sterilizer as conditions may dictate.

The material, when desired, may be saturated or coated with a selected medicament, and then it will successfully serve as a con-

venient means for supplying or replenishing the medicament to an instrument in the hand of the user. Among its many uses, the device may be employed as a cleaner where the 5 cleaning operation requires an abrasive action, and in this event a suitable abrasive material, such as mineral wool or the like, may readily be supported by the device.

When it is desired to remove the material 10 C from the device, the material is pulled from between the gripper members 12 and flanges 13. This releases the device from engagement with the fingers, as shown in Figure 3, and permits its ready removal therefrom. Although this disclosure points out 15 specific uses for the device, it is to be understood that it may be employed in many other uses without departing from the spirit of the invention.

20 In any of the uses of the device the user may frequently wipe or otherwise engage an instrument held in one hand on the material which is held by the device on the other hand without in any way restricting 25 the free use of the hands for other duties.

Having thus described my invention what I claim is:

1. A device of the class described including opposed pivotally-united members, the 30 said members comprising opposed gripper members and opposed finger-engaging portions, the gripper member being constructed to securely grip material therebetween and cooperating with the finger-engaging portions to securely hold the finger-engaging 35 portions in engagement with the user's finger when the material is gripped between the opposed gripper members, the finger-engaging portions being yieldable to permit material 40 of various sizes to be held by the gripper members and to impart gripping stress to the opposed gripper members.

2. A device of the class described including opposed pivotally united members, the 45 said members comprising opposed gripper members and opposed arcuate finger-engaging portions, the gripper members and finger-engaging portions operating in opposition to each other, the finger-engaging portions being yieldable to permit material of 50 various sizes to be held by the gripper mem-

bers and to impart gripping stress to the opposed gripper members.

3. A device of the class described including opposed pivotally united members, the 55 said members comprising opposed rigid gripper members having perpendicularly-disposed gripping flanges and opposed resilient finger-engaging portions, the gripper members and finger-engaging portions operating in opposition to each other.

4. A device of the class described including opposed members, the said members comprising opposed gripper members, opposed arcuate finger-engaging portions and opposed ears positioned between the gripper members and the finger-engaging portions, and means for pivotally uniting the said ears, the finger-engaging portions being 65 yieldable to permit material of various sizes 70 to be held by the gripper members and to impart gripping stress to the opposed gripper members.

5. A device of the class described including opposed pivotally-united members, the 75 said members comprising opposed gripper members, gripping flanges carried by the gripper members, and opposed finger-engaging portions, the finger-engaging portions being yieldable to permit material of various sizes to be held by the gripper members and to impart gripping stress to the 80 opposed gripper members.

6. A device of the class described including opposed pivotally-united members, the 85 said members comprising opposed gripper members and opposed finger engaging portions, the gripper members being constructed to securely grip suitable material therebetween and cooperating with the finger-engaging portions to securely hold the finger-engaging portions in engagement with the user's finger when the material is gripped 90 between the gripper member and to release the finger when the material is removed from the gripper-members, the finger-engaging portions being yieldable to permit material of various sizes to be held by the gripper members and to impart gripping stress to the 95 opposed gripper members.

In testimony whereof I affix my signature.
JOHN T. ASHTON.
